(57) **CLAIM**

I claim the ornamental design for a lamp, as shown.

DESCRIPTION

FIG. 1 is a rear view of a first embodiment of a lamp of my new design,

FIG. 2 is a left side view thereof;

FIG. 3 is a front view thereof;

FIG. 4 is a right side thereof;

FIG. 5 is a top view thereof;

FIG. 6 is a bottom view thereof;

FIG. 7 is a front view of a second embodiment of a lamp of my new design;

FIG. 8 is a left side view thereof;

FIG. 9 is a rear view thereof;

FIG. 10 is a right side view thereof;

FIG. 11 is a top view thereof;

FIG. 12 is a bottom view thereof;

FIG. 13 is a left side view of a third embodiment of a lamp of my new design;

FIG. 14 is a front view thereof (the rear view being symmetrical);

FIG. 15 is a right side view thereof;

FIG. 16 is top view thereof;

FIG. 17 is a bottom view thereof; and,

FIG. 18 is a perspective view thereof.

The lamp of the first embodiment finds particular use as a hanging lamp. The lamp of the fourth embodiment finds particular use as a hanging lamp.
